MOVABLE SPLIT BED FOR FLAT BED PRINTING PRESSES

Filed Dec. 21, 1934

UNITED STATES PATENT OFFICE

2,018,572

MOVABLE SPLIT BED FOR FLAT BED
PRINTING PRESSES

John Ralph Reichenbach, Palmerton, Pa.

Application December 21, 1934, Serial No. 758,638

16 Claims. (Cl. 101—250)

This invention relates to a movable split bed for flat bed printing presses and has for its object to so construct the bed as to enable convenient access thereto to expeditiously change a form when occasion requires.

A further object of the invention is to provide, in a manner as hereinafter set forth, a bed of the class referred to so constructed and arranged whereby the form carried by the bed may be readily removed from under the printing cylinder when changes are desired.

A further object of the invention is to provide, in a manner as hereinafter set forth, a bed of the class referred to so constructed and arranged whereby a form may be quickly and conveniently changed when desired.

A further object of the invention is to provide, in a manner as hereinafter set forth, a bed of the class referred to including a slidably mounted, latchable form carrier permitting for conveniently and expeditiously changing a form when occasion requires.

A further object of the invention is to provide, in a manner as hereinafter set forth, a bed of the class referred to including a slidably mounted, latchable, extendible form carrier permitting for conveniently and expeditiously changing a form, and including means to prevent the form carried thereby from sliding off therefrom during the moving of the carrier to form changing position.

A further object of the invention is to provide, in a manner as hereinafter set forth, a bed of the class referred to including an extendible form carrier and adjustable means coacting with the form retaining means for releasably anchoring the form upon the carrier.

Further objects of the invention are to provide, in a manner as hereinafter set forth, a bed of the class referred to which is comparatively simple in its construction and arrangement, strong, durable, compact, conveniently assembled, readily repaired when occasion requires, thoroughly efficient for the purpose intended thereby, materially decreasing the time now required to change a form enabling the use of a full type form, i. e. the full capacity of a press without the employment of the conventional quoin, and inexpensive to manufacture.

To the above ends essentially, and to others which may hereinafter appear, the invention consists of such parts, and such combination of parts which fall within the scope of the invention as claimed.

In the drawing:

Figure 1 is a top plan view, partly broken away,

of the bed and further showing a form anchored thereon,

Figure 2 is a section on line 2—2, Figure 1, upon an enlarged scale,

Figure 3 is a section on line 3—3, Figure 1, upon an enlarged scale,

Figure 4 is a perspective view of a wedge or locking block,

Figures 5 and 6 are sectional details illustrating the track members or cylinder bearings, and

Figure 7 is a fragmentary view in elevation showing the latching means for the carrier.

The bed, generally indicated at 6, is of the reciprocatory type and, as well known, is associated with an impression cylinder 7 which travels on the top of the bed for the purpose of printing from the form 8.

The bed 6 includes a pair of spaced outer oblong supports 9, 10, a pair of spaced inner oblong supports 11, 12 arranged between the supports 9, 10. The supports are of the same width, height and length. The ends of the supports are rabbeted to form transverse aligning shoulders 13, 14 arranged in close proximity to the lower faces of the supports. A connecting member 15 is mounted upon the shoulders 13 and is connected to one end of the said several supports above the shoulders 13. A connecting member 16 is mounted upon the shoulders 14 and is connected to the other end of the several supports above the shoulders 13. Two spaced parallel sets 17, 18 of upstanding brace members are arranged between and connected to the supports 9, 10, 11 and 12. The brace members are flush with the tops of the supports and have their bottoms arranged above the lower faces of the supports. The brace members of the set 17 oppose in spaced relation the connecting member 15. The outer brace members of the set 17 are provided centrally of the top thereof with rectangular cut-outs 19 for a purpose to be referred to. The brace members of the set 18 oppose in spaced relation the connecting member 16. The outer brace members of the set 18 constitute stops for a purpose to be referred to.

The supports 11 and 12 centrally of the tops thereof, are formed with V-shaped grooves 20 extending from one end to the other thereof. The top edges of members 15, 16 have V-shaped notches forming continuations of the grooves 20.

Secured upon and to the tops of the supports 9, 10 are track members or cylinder bearers 21, 22 respectively for the impression cylinder 7. The track member 22 is of angle-shape in cross-section and formed of a vertical leg 23 and a hori-

zontal leg 24 integral with the outer end of and extending inwardly from leg 24. The track members are flanged at their bottom, as at 25 with respect to track member 21 and as at 26, 27 with respect to member 22. The track members 21, 22 are oppositely beveled, as at 28, 29 respectively forming in connection with supports 9, 10 guide grooves or passages 30, 31 respectively for a carrier to be referred to. The bevels 28, 29 are oppositely disposed. The leg 24 in connection with flange 26 forms an inwardly opening groove 32 for a purpose to be referred to. At the point of mergence of 23 with leg 24 the track member 22 is provided with transversely extending spaced threaded openings 33 extending from the outer side thereof and communicating with the top of the groove 32. The openings 33 incline downwardly throughout from their outer to their inner ends.

20 Connected to the outer face of the member 15 and extended therefrom is an inking plate element 34 including a vertical inner part 35 extending above the top edge of member 15 and formed with a plurality of spaced endwise opposed rectangular openings 36 disposed above member 15.

30 The body structure of the bed has been described as a series of separate elements secured together, but it is obvious that the supports, connecting members, brace members, track members and ink plate structure may be set up from a single casting, or that certain of the elements may be cast together and the other element or elements secured therewith.

35 The bed includes an extendible carrier 39 for the form 8 and which consists of a plate 40 of a size to extend from the bottom of one bevel portion 28 to the bottom of the other bevel portion 29 and to extend from the outer face of member 16 to the outer face of member 15. The plate 40 has its side edges oppositely beveled, as at 41, 42. The said side edges of plate 40 extend into the guide passages formed by the bevels 28, 29 in connection with the supports 9, 10. The plate 40 is slidably mounted upon the inner portions of the tops of the supports 9, 10 and is also slidably mounted upon the tops of the supports 11, 12 as well as the tops of the sets of brace members. The plate 40 has secured to its inner edge a plurality of upstanding spaced stops 43 to prevent the shifting off of the form from the rear end of carrier 39, when the latter is being moved to its extended position for the purpose of changing a form. When the carrier 39 is in non-extended position and supporting a form to be printed from, the stops 43 are arranged within the openings 36. The stops 43 will also act to pull the form along with the carrier when the latter is being moved to extended position for form changing. The carrier 39 at its outer end of its inner face is provided with a transversely extending cutout to provide a ledge 44 for a purpose to be referred to. The lower face of plate 40 is formed with spaced parallel guide strips 44' of V-shape cross section which ride in the grooves 20. The lower face of plate 40 has secured thereto depending abutments 45 which, when the carrier is being extended, pass through openings 19 to abut the outer brace members 18, whereby these latter constitute stops for arresting the outward shifting of the carrier.

70 With respect to Figure 1 the form 8 is shown clamped on the carrier 39 when too large to use a chase and the means for clamping it will now be described.

Threadedly engaging with the walls of the opening 33 are combined adjusting and clamping screws 46 for engaging spaced beveled parts at the upper inner corner 46' of a steel block 47, to force the latter against an end of form 8. The block 47 is arranged within and extended from groove 32. A steel bar 47' bears against one side of form 8. The bar 47' extends from one track member to the other and bears against the stops 43. The form 8 at its other end bears against the inner face of track member 21. At the other side of form 8 is arranged a wooden bar 50 and spaced from the latter is a steel bar 51. Interposed between the bars 50 and 51 are quoins 52, and interposed between the bar 51 and clamps 55 is the wood furniture 53 which is arranged over ledge 44.

There are times when forms are of such size that a chase cannot be placed around them. In that case steel bars are placed in front and in back of the type form and quoins are used to lock or squeeze the type securely on the bed. When there is no room left for quoins on bearer side a sort of wedge is used, but this is very unsatisfactory as it will jump out at times during the rapid motion of the press. This objection is overcome by placing the block 47 in the groove 32 as the upper wall thereof will prevent the jumping out of the wedge.

30 The track members 21, 24 have their upper edges formed with a toothed rack 54.

35 The carrier 39 is latched in form holding position by spaced clamps 55 which are pivotally connected to the member 16 and coact with the wedging bar 56 which may be welded or otherwise secured to the lower portion of the outer face of member 16. The clamps 55 are to be swung upwardly binding or locking the plate 40 and in turn hold the wood furniture 53 while the quoins 52 are tightened. The bottoms of the 40 clamps 55 coact from a wedging standpoint with bar 56 whereby they will be held in clamping position relative to plate 40. The clamps 55 are eccentrically pivoted and have rounded lower ends. Although it is to be understood that any 45 suitable means may be employed for latching the carrier 39 in form holding position with respect to the other elements of the bed.

50 The plate 40 has its outer end formed with an apertured extension 57 for use to move the carrier in opposite directions upon its supporting structure, and further for coaction with ledge 44 to support a galley when occasion requires.

55 The supports 9, 10, 11, 12, bracing members 17, 18, and track members 22, 23 constitute a supporting structure for the carrier and for the ink plate element.

What I claim is:

1. A printing press bed comprising a mobile supporting structure, a carrier slidably mounted in and extendible from one end of said structure and adapted to support a form locked thereupon, an ink plate forming element anchored to the other end of said structure, upstanding stops on the inner end of the carrier, said element having means for housing said stops when the carrier is in form supporting position, and means carried by said structure for latching the carrier therein.

2. A printing press bed comprising a mobile supporting structure, a carrier slidably mounted in and extendible from one end of said structure and adapted to support a form locked thereupon by suitable means, an ink plate forming element anchored to the other end of said structure, upstanding stops on the inner end of the carrier,

- said element having means for housing said stops when the carrier is in form supporting position, means carried by said structure for latching the carrier therein, and combined adjusting and 5 clamping means for the said suitable parts employed for locking the form upon the carrier, the said combined adjusting and clamping means being adjustably connected to said structure.
3. A printing press bed comprising a mobile 10 supporting structure, a carrier slidably mounted in and extendible from one end of said structure and adapted to support a form locked thereupon by suitable means, an ink plate forming element anchored to the other end of said structure, up- 15 standing stops on the inner end of the carrier, said element having means for housing said stops when the carrier is in form supporting position, means carried by said structure for latching the carrier therein, and combined adjusting 20 and clamping means for the said suitable furniture, employed for locking the form upon the carrier, the said combined adjusting and clamping means being adjustably connected to one side of said structure above said carrier.
- 25 4. A printing press bed comprising a mobile supporting structure, a carrier slidably mounted in and extendible from one end of said structure and adapted to support a form locked thereupon by locking furniture in the form of sidewise op- 30 posed blocks, an ink plate forming element anchored to the other end of said structure, up- standing stops on the inner end of the carrier, said element having means for housing said stops when the carrier is in form supporting position, 35 means carried by said structure for latching the carrier therein, and combined adjusting and clamping means for the locking furniture employed for locking the form upon the carrier, the said combined adjusting and clamping means being adjustably connected to one side of said structure and extending at a downward inclination 40 from the outer to the inner end thereof.
5. A printing press bed comprising a mobile supporting structure, a carrier slidably mounted in and extendible from one end of said structure and adapted to support a form locked thereupon by locking furniture in the form of sidewise op- 45 posed blocks, an ink plate forming element anchored to the other end of said structure, up- standing stops on the inner end of the carrier, said element having means for housing said stops when the carrier is in form supporting position, 50 means carried by said structure for latching the carrier therein, and combined adjusting and clamping means for the locking furniture employed for locking the form upon the carrier, the said combined adjusting and clamping means being adjustably connected to one side of said structure above said carrier, the said side of said 55 structure being formed with a groove in its inner face for the reception of the outer locking block of the locking furniture.
6. In a printing press bed, a mobile supporting structure provided with an upstanding cylinder- 60 bearer at each side thereof, said bearers being provided with means to form said structure with a pair of spaced parallel guide passages, a carrier slidably mounted between said bearers, positioned in said passages, extendible from one end of said 65 structure and adapted to support a form locked thereupon, said carrier including upstanding stop means at its inner end, and means carried by said structure for latching the carrier therein.
7. In a printing press bed, a mobile supporting 70 structure provided with an upstanding cylinder- 75
- bearer at each side thereof, said bearers being provided with means to form said structure with a pair of spaced parallel guide passages, a carrier slidably mounted between said bearers, positioned in said passages, extendible from one end of said structure and adapted to support a form locked thereupon, said carrier including upstanding stop means at its inner end, means carried by said structure for latching the carrier therein, said structure being formed with 10 guide grooves below the carrier and inwardly adjacent to said bearers, and said carrier having depending guide strips travelling in said grooves.
8. In a printing press bed, a mobile supporting structure provided with an upstanding cylinder- 15 bearer at each side thereof, said bearers being provided with means to form said structure with a pair of spaced parallel guide passages, a carrier slidably mounted between said bearers, positioned in said passages, extendible from one end of said 20 structure and adapted to support a form locked thereupon, said carrier including upstanding stop means at its inner end, means carried by said structure for latching the carrier therein, and said structure and carrier having coacting means 25 for arresting the extendible movement of the carrier, the said coacting means being arranged below said guide passages.
9. In a printing press bed, a mobile supporting structure provided with an upstanding cylinder- 30 bearer at each side thereof, said bearers being provided with means to form said structure with a pair of spaced parallel guide passages, a carrier slidably mounted between said bearers, positioned in said passages, extendible from one end of said 35 structure and adapted to support a form locked thereupon, said carrier including upstanding stop means at its inner end, means carried by said structure for latching the carrier therein, said structure being formed with guide grooves below 40 the carrier and inwardly adjacent to said bearers, said carrier having depending guide strips travelling in said grooves, and said structure and carrier having coacting means for arresting the extendible movement of the carrier, the said co- 45 acting means being arranged below said guide passages.
10. In a printing press bed, an open top mobile supporting structure, a carrier slidably supported within said structure below the top of the latter and adapted to support a form locked thereupon, said carrier being extendible from one end of said structure, said carrier and structure having coacting interengaging guide means for the carrier below the bottom of the latter, said structure being formed with guide passages for the 50 sides of the carrier, means for latching the carrier within said structure, and said carrier and structure having coacting means arranged below the bottom of the carrier for arresting the ex- 55 tendible movement of the latter.
11. In a printing press bed, an open top mobile supporting structure, a carrier slidably supported within said structure below the top of the latter and adapted to support a form locked thereupon, 60 said carrier being extendible from one end of said structure, said carrier and structure having coacting interengaging guide means for the carrier below the bottom of the latter, said structure being formed with guide passages for the 65 sides of the carrier, means for latching the carrier within said structure, said carrier and structure having coacting means arranged below the bottom of the carrier for arresting the extendible 70 movement of the latter, an ink plate forming 75

- element secured to the other end of said structure, said carrier being formed with upstanding stop means, and said element being provided with means for housing said upstanding stop means when the carrier is latched in said structure.
12. In a printing press bed, an open top mobile supporting structure, a carrier slidably supported within said structure below the top of the latter and adapted to support a form locked thereupon by suitable means, said carrier being extendible from one end of said structure, said carrier and structure having coacting interengaging guide means for the carrier below the bottom of the latter, said structure being formed with guide passages for the sides of the carrier, means for latching the carrier within said structure, said carrier and structure having coacting means arranged below the bottom of the carrier for arresting the extendible movement of the latter, and combined adjusting and clamping means for the said suitable means employed for locking the form upon the carrier, the said combined adjusting and clamping means being adjustably connected to said structure.
13. In a printing press bed, an open top mobile supporting structure, a carrier slidably supported within said structure below the top of the latter and adapted to support a form locked thereupon by suitable means, said carrier being extendible from one end of said structure, said carrier and structure having coacting interengaging guide means for the carrier below the bottom of the latter, said structure being formed with guide passages for the sides of the carrier, means for latching the carrier within said structure, said carrier and structure having coacting means arranged below the bottom of the carrier for arresting the extendible movement of the latter, an ink plate forming element secured to the other end of said structure, said carrier being formed with upstanding stop means, said element being provided with means for housing said upstanding stop means when the carrier is latched in said structure, and combined adjusting and clamping means for the said suitable means employed for locking the form upon the carrier, the said combined adjusting and clamping means being adjustably connected to said structure.
14. In a printing press bed, an open top mobile supporting structure, a carrier slidably supported within said structure below the top of the latter and adapted to support a form locked thereupon by locking furniture, said carrier being extendible from one end of said structure, said carrier and structure having coacting interengaging guide means for the carrier below the bottom of the latter, said structure being formed with guide
- passages for the sides of the carrier, means for latching the carrier within said structure, said carrier and structure having coacting means arranged below the bottom of the carrier for arresting the extendible movement of the latter, and combined adjusting and clamping means for the locking furniture employed for locking the form upon the carrier, the said combined adjusting and clamping means being adjustably connected to one side of said structure above said carrier.
15. In a printing press bed, an open top mobile supporting structure, a carrier slidably supported within said structure below the top of the latter and adapted to support a form locked thereupon by locking furniture, said carrier being extendible from one end of said structure, said carrier and structure having coacting interengaging guide means for the carrier below the bottom of the latter, said structure being formed with guide passages for the sides of the carrier, means for latching the carrier within said structure, said carrier and structure having coacting means arranged below the bottom of the carrier for arresting the extendible movement of the latter, and combined adjusting and clamping means for the locking furniture employed for locking the form upon the carrier, the said combined adjusting and clamping means being adjustably connected to one side of said structure and extending at a downward inclination from the outer to the inner end thereof.
16. In a printing press bed, an open top mobile supporting structure, a carrier slidably supported within said structure below the top of the latter and adapted to support a form locked thereupon by locking furniture in the form of sidewise opposed blocks, said carrier being extendible from one end of said structure, said carrier and structure having coacting interengaging guide means for the carrier below the bottom of the latter, said structure being formed with guide passages for the sides of the carrier, means for latching the carrier within said structure, said carrier and structure having coacting means arranged below the bottom of the carrier for arresting the extendible movement of the latter, and combined adjusting and clamping means for the locking furniture for locking the form upon the carrier, the said combined adjusting and clamping means being adjustably connected to one side of said structure above said carrier, the said side of said structure being formed with a groove in its inner face for the reception of the outer locking block of the locking furniture.

JOHN RALPH REICHENBACH.
